UNITED STATES PATENT OFFICE.

CHARLES J. FOLLMER, OF NEW YORK, N. Y.

DESIGN FOR A PARASOL.

47,103.

Specification for Design.

Patented Mar. 16, 1915.

Application filed January 8, 1915. Serial No. 1,247. Term of patent 14 years.

To all whom it may concern:

Be it known that I, CHARLES J. FOLLMER, a citizen of the United States, residing at New York, in the county of New York and State of New York, have invented a new, original, and ornamental Design for Parasols, of which the following is a specification, reference being had to the accompanying drawing, forming a part thereof.

Figure 1 is a side elevation of the parasol

showing my design and Fig. 2 is a plan view thereof.

I claim:—

The ornamental design for parasol as shown.

CHARLES J. FOLLMER.

Witnesses:

Wm. N. McCONNELL,
L. MELFI.
